(57) CLAIM

The ornamental design for a lure/fish hook retriever, as shown and described.

DESCRIPTION

FIG. 1 is an enlarged front perspective view of the head portion of the lure/fish hook retriever showing my new design;

FIG. 2 is an enlarged side elevation view of the head portion; FIG. 3 is an enlarged opposite side elevation view of the head portion;

FIG. 4 is an enlarged top plan view of the head portion; FIG. 5 is an enlarged bottom plan view of the head portion; and,

FIG. 6 is a perspective view of the lure/fish hook retriever. The top portion of the lure/fish hook retriever is shown broken away for convenience of illustration.
